US00D961565S

(12) **United States Design Patent** (10) **Patent No.:** **US D961,565 S**
(45) **Date of Patent:** **** Aug. 23, 2022**

(54) **ELECTRONIC DEVICE**

(71) Applicant: **Samsung Electronics Co., Ltd.**, Suwon-si (KR)

(72) Inventors: **Kangmoon Kim**, Suwon-si (KR); **Junho Jin**, Suwon-si (KR); **Dahyun Lee**, Suwon-si (KR); **Wonkyu Sung**, Suwon-si (KR)

(73) Assignee: **SAMSUNG ELECTRONICS CO., LTD.**, Suwon-si (KR)

(**) Term: **15 Years**

(21) Appl. No.: **29/725,471**

(22) Filed: **Feb. 25, 2020**

(30) **Foreign Application Priority Data**

Aug. 26, 2019 (KR) 30-2019-0040734

(51) **LOC (13) Cl.** **14-03**

(52) **U.S. Cl.**

USPC **D14/248**

(57) **CLAIM**

The ornamental design for an electronic device, as shown and described.

DESCRIPTION

FIG. 1 is a front perspective view of an electronic device showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a rear perspective view thereof.

The dashed broken lines in the drawings depict portions of the electronic device that form no part of the claimed design.

1 Claim, 8 Drawing Sheets
